FREDERICK M. STEVENS, OF NEW YORK, N. Y., ASSIGNOR TO MANHATTAN SCREW & STAMPING WORKS, OF NEW YORK, N. Y., A CORPORATION OF NEW YORK.

LAMP.

971,323.

Specification of Letters Patent. Patented Sept. 27, 1910.

Application filed October 21, 1909. Serial No. 523,776.

To all whom it may concern:

Be it known that I, FREDERICK M. STEVENS, a citizen of the United States, and a resident of the borough of Manhattan, city and county of New York, State of New York, have invented certain new and useful Improvements in Lamps, of which the following is a specification.

My invention relates particularly to that class of portable or semi-portable lamps which are used for illumination and warning in connection with automobiles, vehicles, boats, etc.; the improvements to be set forth are, however, also of advantage in connection with stationary lamps for various purposes.

The object of my invention is to provide an improved and simplified structure having a small number of parts adapted to be easily and quickly constructed, assembled and disassembled.

A further object of my invention is to provide a casing for a lamp of the class described which shall combine strength and lightness.

A still further object of my invention is to provide a casing to which the component parts of the lamp structure are so attached as to leave the external surface of said casing substantially free from rivets, screws, projections or surface breaks of any kind.

Another object of my invention is to provide a lamp the parts of which have been assembled substantially without the use of solder.

In the drawing, which is hereby made a part of this specification, Figure 1 shows in side elevation a preferred form of my invention as commonly used for automobiles; Fig. 2 is a central longitudinal section, partly in elevation, corresponding to Fig. 1; Fig. 3 is a section partly in elevation, along the line 3—3 of Fig. 2; and Fig. 4 is a central section through the reflector of the lamp and its mounting.

The lamp consists essentially of a casing comprising a central section 1 to which is attached a hinged front 2 and a permanently attached rear section 3, said rear section being provided with a reflector 4 and the front with a glass 5. Mounted within the casing at a suitable distance from the reflector is a burner 6 which may be of any usual construction.

What may perhaps be called the central idea of my invention is the use of a casing the walls of which, for substantially the entire casing, are double comprising an outer layer of brass or similar ornamental sheet metal and an inner layer of sheet iron or other equivalent strong and inexpensive material. Most of the lamp parts aside from the casing are fixed to this inner shell which is then covered with the outer shell so that the points of attachment of said parts are not seen when the lamp is assembled.

Referring to the central section 1, an outer tube 7 of thin brass fits snugly over an inner tube 8 of somewhat thicker sheet iron; the brass tube is somewhat longer than the iron tube and in assembling is so placed as to project beyond the iron tube at each end, said projecting portion being then turned over inwardly upon the ends of the iron tube so as to clamp the two tubes firmly together. A rectangular opening is then cut through both tubes at the top and through said opening is passed the ventilating cap 9. This cap consists of an outer layer 10 of sheet brass and an inner strip 11 of sheet iron. The brass is shaped like a closed box opened below and having extensions 12 on each of two opposite sides adjacent to the opening said extensions being carried inwardly, downwardly and then outwardly so as to tightly embrace the edges of the opening of the casing, thus fixing the ventilating cap in the opening of the casing. The inner sheet iron piece 11 being intended mainly to receive and absorb the intense and direct heat of the burner is only provided of sufficient area to cover the inner top surface of cap 9; tongues 12' integrally formed upon strip 11 at the same two opposite sides of the cap as are the extensions 12 bent downwardly and sprung outwardly as to said strip serve to keep said strip in position against the superposed brass strip.

In the bottom of the central section 1 is formed a slot 12² with its length parallel to the lamp axis and wide enough to take the burner supply tube 12³. Plates 12⁴, 12⁴ and a nut 12⁵ threaded upon tube 12³ allow the flame height to be raised or lowered and the burner as a whole to be clamped at any desired point in the length of the slot thus enabling accurate adjustment of the flame to be made for reflectors of differing curvature.

and to compensate for other variations in individual lamps.

Projecting from each side of the central section 1 of the casing and preferably in the central plane thereof is a rectangular sectioned lug 13 vertically bored as at 13' and having a clamp screw 14 so as to fit upon and be locked to such suitable fork or support as may be provided. Each lug is provided with an inner flanged portion 15 adapted to engage the casing, the lug proper being of smaller section and thrust from the inside through a similar opening in the casing just large enough to receive it. Rivets 16 previously fixed in the inner shell 8 and adapted to engage holes placed in the flange are then upset so as to hold the lugs securely. Placed about the interior of section 1 are angle pieces 17; these are riveted at 18 to the inner shell 8 before the outer brass portion 7 is put on.

The rear section 3, like the central section 1, is composed of an outer spun brass cap 19 fitted closely to an inner cap 20 of sheet iron and exactly similar shape. The edges of cap 19 are spun inwardly so as to cover the edge of 20 and hold the two pieces together. Before thus covering the inner cap 20, four stiff brackets 21 are riveted to said inner cap. These brackets are each bent so as to have an inwardly projecting V at 22 and an inwardly projected terminal portion 23 parallel to similar inwardly bent portions 22' of angle pieces 17.

The reflector 4, which is of glass of suitable curvature, is held in a sheet iron mounting comprising a back 24 shaped to correspond with the curvature of 4 and against which the reflector lies, and a retaining piece 40 25 into the tubular portion of which 26 the reflector is inserted from the rear; an inwardly turned edge, 27, engages the periphery of the reflector and with the back 24 holds it in place. To prevent back 24 from slipping out it is formed with a tubular rim 28 adapted to fit snugly within 26 and inwardly over this rim, the edge of which is preferably beaded, are folded tongues 29 (shown dotted Fig. 4) formed by radially 45 slitting the flared rear portion 29' of the retaining piece.

In order that the reflector may be held firmly and yet yieldingly in its mount and thus expand and contract without danger 55 of breaking as the burner is lighted and extinguished a pad of asbestos 30 or other similar material of heat resisting qualities may be placed between the reflector and the back 24. With the same object in view, 60 also, I prefer to cut away centrally from the back 24 a substantial portion, say an area equal to about one half that of the entire back.

The reflector and its mount as just described are held against the rear section 3

by the V's 22 of the brackets 21 the brackets being given an initial inward spring and being so spaced about the back as to fit within the peripheral slots 31 left by the inward folding of the tongues 29. Since the flared segments of 29' by reason of the slots 31 are springy it is possible by suitably determining the distance of the V's from rear section 3 to hold the reflector and its mount firmly in place without the necessity of forming the brackets 21 and the reflector mount with great exactness.

After the reflector has been fixed to rear section 3 as above described the rear section as a whole is united to the central section 1 by slipping it over the edge thereof until the two beads 32 are abutting and then drawing up screws 33 which engage the parallel segments of angle pieces 17 and brackets 21.

Referring to the hinged front 2, this comprises a tubular section 34, beaded on the edge adjacent to section 1, and having its other edge spun outwardly, then forwardly and then inwardly so as to form a rim 34' of hook shaped section; the minimum diameter of this inwardly turned portion is at its edge and is substantially less than the diameter of the cylindrical portion. Slipped within the front is a split ring 35, which may be of sheet iron, this ring having formed upon it an annular convexity 36 engaging a similar convexity 37 formed in 2. The glass 38 fits within the ring 35 and is pushed up against the edge; it is held in this position by a split spring ring 39 which fits in the groove 37.

By having the diameter of ring 34' at its free edge substantially less than the diameter of the tubular portion 34, the inwardly projecting portion of this rim serves as a diaphragm to cut off a large percentage of the irregularly reflected rays proceeding from the inner periphery of the central section 1.

It will be seen that my improved lamp is composed of but few and simple parts which may be easily and quickly assembled and which when thus assembled are held positively and permanently. The construction results in a minimum number of breaks in the outer surface of the casing, involves substantially no rivets fixed therein, uses no solder and produces a casing rich and elegant in appearance which may be quickly and inexpensively given a high finish.

Various modifications of detail may be made without departing from the spirit of my invention as set forth in the claims.

I claim—

1. In a lamp of the class described the combination with a casing comprising a central section provided with an outer and an inner wall and a rear section provided with an outer and an inner wall, of means independent of said outer walls adapted to hold said

casing sections together, as and for the purpose described.

2. In a lamp of the class described, the combination with a casing comprising a central section provided with an outer and an inner wall and a rear section provided with an outer and an inner wall, of means attached to said inner walls adapted to hold said sections together, as and for the purpose described.

3. In a lamp of the class described, the combination with a casing comprising a central section provided with an outer and an inner wall and a rear section provided with an outer and an inner wall, of angle pieces fixed to the inner wall of said central section, brackets fixed to the inner wall of said rear section said brackets being adapted to hold a reflector yieldingly, and means uniting said angle pieces and said brackets to hold said central and rear sections together, as and for the purpose described.

4. In a lamp of the class described having a casing provided with a rear section, the combination with said rear section of a reflector, a mounting for said reflector comprising a back provided with a tubular rim and a retaining piece also provided with a tubular rim said back and retaining piece being adapted to hold the reflector between them and to have their tubular rims slip one within the other, means for holding said back and retaining piece together, and means for attaching said mounting to said rear section, as and for the purpose described.

5. In a lamp of the class described the combination of a central section and a rear section each provided with an inner and an outer wall, a reflector, brackets attached to the rear section independent of its outer wall to hold the reflector in position, and means attached to the central section independent of its outer wall adapted to engage the

brackets and hold said sections together, as and for the purpose described. 45

6. In a lamp of the class described, the combination of a central section and a rear section, each provided with an inner and an outer wall, a reflector, and means independent of said outer walls serving both to unite 50 said sections together and to secure said reflector, as and for the purpose described.

7. In a lamp of the class described, the combination of a central section and a rear section, each provided with an inner and an 55 outer wall, a reflector and means independent of said outer walls serving both to unite said sections together and to resiliently secure said reflector, as and for the purpose described. 60

8. In a lamp of the class described, the combination of a central section and a rear section each provided with an inner wall, a reflector, a mount for said reflector provided with flared segments, and means serving 65 both to unite said sections and to secure said mount with its flared segments against said rear section, as and for the purpose described.

9. In a lamp of the class described, the 70 combination of a central section, a rear section, a reflector mount provided with flared segments adapted to resiliently space said mount from said rear section, means adapted to resiliently engage said mount and hold 75 it against said rear section, and means adapted to engage said first named means so as to hold said sections together, as and for the purpose described.

In testimony whereof I have hereunto set 80 my hand in the presence of two subscribing witnesses.

FREDERICK M. STEVENS.
